(57) **CLAIM**

The ornamental design for a ultrasonic humidification generation module, as shown and described.

DESCRIPTION

FIG. 1 is a front perspective view of a ultrasonic humidification generation module according to the new design;
FIG. 2 is a front elevational view thereof;
FIG. 3 is a rear elevational view thereof;
FIG. 4 is a left side elevational view thereof;
FIG. 5 is a right side elevational view thereof;
FIG. 6 is a top plan view thereof; and,
FIG. 7 is a bottom plan view thereof.
